UNITED STATES PATENT OFFICE

EDWARD K. MADAN, OF MAPLEWOOD, NEW JERSEY

DESIGN FOR A COMBINATION PENCIL AND LETTER OPENER

Application filed August 28, 1929. Serial No. 32,576. Term of patent 7 years.

To all whom it may concern:

Be it known that I, EDWARD K. MADAN, a citizen of the United States, and residing at Maplewood, in the county of Essex and State of New Jersey, have invented a new, original, and ornamental Design for a Combination Pencil and Letter Opener, of which the following is a specification, reference being had to the accompanying drawing, forming part thereof.

Fig. 1 is a side view of the device; and
Fig. 2 is a side view at right angles to that shown in Fig. 1.

I claim:—
The ornamental design for a combination pencil and letter opener, as shown.

EDWARD K. MADAN.
